HAIR CURLER

Daniel B. Webster, Beachmont, Mass., assignor
of thirty-five per cent to William Neary, Win-
throp, Mass.

Application August 18, 1938, Serial No. 225,517

6 Claims. (Cl. 132—33)

This invention relates to hair curlers for use in dressing women's hair and it has for its object to provide an improved device of this class.

To this end I have provided an improved hair curler having the features of construction and operation set forth in the following description, the several novel features of the invention being separately pointed out and defined in the claims at the close thereof.

10 In the accompanying drawing:

Figure 1 is a side elevation of a hair curler constructed in accordance with my invention.

Figure 2 is an enlarged end elevation of the curler shown in Fig. 1.

15 Figure 3 is a section on line 3—3 of Fig. 2.

Figure 4 shows the curler of Fig. 1 as viewed in plan.

Figure 5 shows the curler as viewed from another angle and with a portion thereof in section on line 5—5 of Fig. 2.

20 Figures 6 and 7 are, respectively, side elevation and plan view of the new bobby-pin hereinafter referred to.

Figure 8 illustrates the use of my improved hair curler.

The illustrated embodiment of my invention is in the form of a straight metal spindle comprising a handle portion 10 at one end thereof and a body portion 11 at the opposite end thereof. The body portion 11 is of more or less tubular form and is made at opposite sides thereof with longitudinal slots 12 which provide two oppositely disposed tines 13 and 14. Each of these two tines is formed upon its exterior with two longitudinal grooves 15 which extend the full length of the body portion 11, said body portion being somewhat larger in diameter than the diameter of the handle portion 10 so that each of the grooves 15 is open at its opposite ends.

40 Within the tubular body portion 11 is a longitudinally disposed metal bow spring 16 whose oppositely disposed branches or legs are in part straight and normally fit flatwise together as shown in Fig. 3, the extremities of said legs or branches being bent outwardly so as to fit against the interior of the body portion near the free end thereof while the intermediate portion of said spring is wedged securely within the inner end of the body portion 11. This spring 16 is, 45 as shown in Fig. 5, made from flat wire bent at its middle to form an eye 17 that is wedged tightly into the body portion 11 and the two parallel legs or branches 18 and 19. The spring 16 is positioned within the body portion 11 so that 50 a plane coincident and parallel with the longi-

tudinal medial lines of the two slots 12, 12 is also coincident and parallel with the plane of the joint between the two legs 18 and 19 of the spring.

In using this device the forked or slotted body portion 11 is forced endwise onto a lock of hair so that the latter will occupy the slots 12, 12 and also occupy a position between the legs or branches 18 and 19 of spring 16 as shown conventionally in Fig. 5 at 20.

10 Figure 8 of the drawing illustrates the manner in which the body portion is shoved endwise into position upon the lower end of a lock of hair 21 with the said lock gripped by spring 16. Then while holding the opposite ends of the device, as illustrated in Fig. 8, the said device is rotated in a direction to wind the lock 21 upon the exterior thereof as indicated conventionally at 22 in Fig. 5. When the desired amount of the lock 21 has been wound upon the device a metal 15 bobby-pin such, for example, as that shown at 23 in Figs. 5, 6 and 7, is slid into one of the grooves 15 from either end thereof whereupon the body portion 11 is withdrawn endwise from the curl leaving the bobby-pin in position thereon.

20 Any suitable form of bobby-pin may be employed in connection with my device but the one illustrated in Figs. 6 and 7 possesses some distinctive advantages. This bobby-pin is made from a length of flat wire which is bent transversely at two places intermediate its end so that the opposite end portions thereof normally fit flatwise against each other and provide two clamped jaws 24 and 25, the free end of the latter extending beyond the former and made, if desired, with a point 26. The intermediate portion 27 of the bent wire provides a spring arm which yieldingly urges the jaw 24 toward the jaw 25 and this spring arm is bent upwardly as at 28 to provide a finger piece by means of which 25 the bobby-pin can be conveniently handled and also so as to provide a rounded or beveled surface or portion 29.

30 After winding the curl onto the body portion 11 the jaw 25 of the bobby-pin 23 is laid within 45 the exposed end portion of one of the grooves 15 indicated by dotted lines in Fig. 4 and then by means of the finger piece 28 the bobby-pin is slid longitudinally within its groove 15 toward the curl with the result that the beveled portion 29, 50 Fig. 6, of the bobby-pin guides the jaw 24 upwardly onto the curl so that it will occupy the position shown in Fig. 5. It will be clear from Fig. 5 of the drawing that by providing the two parallel jaws 24 and 25 disposed side by side and 55

connected by the arm 27 enables the jaws 24 and 25 to assume relatively parallel positions, or approximately so, when the bobby-pin is in position upon a curl.

It will also be clear from the above description that the spring 16 permits the lock of hair to slide into position between the jaws 18 and 19 and that while it is in this position said spring firmly grips the lock and prevents it from slipping out of the slots 12 of the body portion 11.

Each tine 13 and 14 of the body portion 11 is made with two grooves, as above described, and these grooves 15 are, as shown in Fig. 2, faced apart equi-distant so that always there will be a groove 15 closely adjacent the scalp at the completion of winding the curl.

As shown in the drawing, the tine 13 is made longer than the tine 14 and adjacent to its free end is beveled as at 30 in order to facilitate and assist the entrance of the lock of hair into the slot 12 of the spindle when the latter is shoved endwise on to said lock preparatory to winding it upon the spindle.

At its opposite end the spindle 10-11 is made with a flatish point 31 for use by the operator in segregating or lifting a lock of hair away from the head of the subject preparatory to sliding the slotted end of the spindle endwise on said lock.

What I claim is:

1. A hair curler consisting of a spindle made at its one end with a body portion and at its opposite end with a handle portion, said body portion being made with a pair of relatively parallel longitudinal tines which are spaced apart to provide between them a longitudinal slot that is open at one end and adapted to receive within it a lock of hair, and said tines being made upon their exteriors with longitudinal grooves each adapted to receive one of the jaws of a bobby pin after a lock of hair has been wound upon said tines, and a lock-holding bow spring confined in position between said two tines, said bow spring comprising a pair of opposed parallel legs between which said lock is forced when it is slid into position between said tines and by which said lock is held within said slot while it is being wound upon said tines.

2. A hair curler consisting of a spindle made at its one end with a tubular body portion and at its opposite end with a handle portion, said body portion comprising a pair of relatively parallel longitudinal tines which are spaced apart to provide between them a longitudinal slot that is open at one end and adapted to receive within it a lock of hair, and said tines being made upon their exteriors with longitudinal grooves each adapted to receive one of the jaws of a bobby pin after a lock of hair has been wound upon said

tines, and a lock-holding bow spring confined in position between said two tines, said bow spring comprising a pair of opposed parallel legs between which said lock is forced when it is slid into position between said tines and by which said lock is held within said slot while it is being wound upon said tines and the outer end portions of said legs being divergently curved away from each other so as to guide the lock of hair into position between said legs.

3. A hair curler consisting of a spindle made at its one end with a pair of longitudinal relatively parallel tines which are spaced apart to provide between them a longitudinal slot that is open at one end and adapted to receive within it a lock of hair, and a lock-holding bow spring confined in position between said two tines, said bow spring comprising a pair of opposed longitudinally disposed parallel legs whose outer end portions diverge and between which said lock is forced when it is slid into position between said tines so that said lock is held within said slot by said bow spring while it is being wound upon said tines.

4. A hair curler consisting of a spindle made at its one end with a pair of longitudinal relatively parallel tines which are spaced apart to provide between them a longitudinal slot that is open at one end and adapted to receive within it a lock of hair, one of said tines being made longer than the other and having its extremity beveled upon its inner side to guide a lock of hair into said slot.

5. A hair curler constructed in accordance with claim 4 wherein the opposite end of said spindle is made with a flatish point for use in segregating a lock of hair that is to be curled.

6. A hair curler consisting of a spindle made at its one end with a body portion that is relatively large in cross-section and at its opposite end with a handle portion that is relatively small in cross-section and provided with a pointed extremity, said body portion being made with a pair of relatively parallel longitudinal tines which are spaced apart to provide between them a longitudinal slot that is open at one end and adapted to receive within it a lock of hair, and said tines being made upon their exteriors with longitudinal grooves each adapted to receive one of the jaws of a bobby pin after a lock of hair has been wound upon said tines, and a lock-holding bow spring confined in position between said two tines, said bow spring comprising a pair of opposed parallel legs between which said lock is forced when it is slid into position between said tines and by which said lock is held within said slot while it is being wound upon said tines.

DANIEL B. WEBSTER.
